(57) **CLAIM**

The ornamental design for a cover for reinforcing bar, as shown and described.

DESCRIPTION

FIG. 1 is an upper perspective view of a cover for reinforcing bar.

FIG. 2 is a lower perspective view of the cover for reinforcing bar of FIG. 1.

FIG. 3 is a top view of the cover for reinforcing bar of FIG. 1.

FIG. 4 is a bottom view of the cover for reinforcing bar of FIG. 1.

FIG. 5 is a front of the cover for reinforcing bar of FIG. 1, with a rear view being a mirror image thereof; and,

FIG. 6 is a 30-degree rotated front view of the cover for reinforcing bar of FIG. 1, with a rear view at this rotation being a mirror image thereof.
